UNITED STATES PATENT OFFICE

119,752

DESIGN FOR A CLOTHES HAMPER

Ota O. Hobson, Chariton, Iowa

Application August 8, 1938, Serial No. 79,194

Term of patent 3½ years

To all whom it may concern:

Be it known that I, Ota O. Hobson, a citizen of the United States, resident of Chariton, Lucas County, Iowa, have invented a new, original, and ornamental Design for a Clothes Hamper, of which the following is a specification, reference being had to the accompanying drawing, forming a part thereof.

Fig. 1 is a front perspective view of the article showing my design, with the lid in open position; and

Fig. 2 is a transverse sectional view, taken along line 2—2 of Fig. 1.

The perforations shown are continued throughout the article.

I claim:

The ornamental design for a clothes hamper, substantially as shown and described.

OTA O. HOBSON.
